UNITED STATES PATENT OFFICE

SIGMUND BAUER, DECEASED, LATE OF OBERWARTH, BURGENLAND, AUSTRIA, BY
REGINA LÖWY, ADMINISTRATRIX, OF OBERWARTH, BURGENLAND, AUSTRIA, AS-
SIGNOR TO JULIA LOWY, OF NEW YORK, N. Y.

ROOFING CONSTRUCTION

Application filed March 20, 1929. Serial No. 348,596.

This invention relates to improvements in roofing constructions, and has particular reference to metallic roofing plates.

An object of the invention is to provide an improved roofing construction wherein enamelled sheet metal plates having a comparatively small manufacturing cost are so formed and assembled as to provide a secure and very tight joint between adjacent plates.

Another object is to reinforce the plates both longitudinally and transversely thereof so that their thickness can be materially reduced.

A further object is to form one edge of a plate with a flange which is parallel to the plate and which engages a next adjacent plate in such manner as to provide an effective seal for the exclusion of moisture.

The above and other objects will appear more clearly from the following detailed description, when taken in connection with the accompanying drawing, which illustrates preferred embodiments of the inventive idea.

In the drawing—

Figure 1 is a plan view of one of the plates constructed in accordance with the invention;

Figure 2 is a section on the line 2—2 of Figure 1;

Figure 3 is a section taken substantially on the line 3—3 of Figure 1;

Figure 4 is a longitudinal section showing the manner of assembling the various plates constituting the roofing construction;

Figure 5 is a plan view of one of the hook members forming a part of the invention and the means for securing said hook member to the under side of a plate; and

Figure 6 is a fragmentary perspective view showing a slightly modified form of the invention.

The roofing plate 1, comprising the essential features of the invention, is preferably made of enamelled sheet metal having its lateral or side edges bent, as shown in Figure 3, with one of the edges provided with a rib 2 and the other with a corresponding depression or groove 3, so that in assembling the side edges of two adjacent plates the rib 2 of one plate is forced by spring action into the groove 3 of the other plate so as to firmly

hold said plates together in the same horizontal plane.

In the body portion of each plate 1 there are formed spaced transverse and longitudinal stiffening or reinforcing ribs 4 and 5, respectively, the ribs 4 being preferably of oval formation. Said ribs 4 and 5 alternate with each other in the longitudinal direction of the plate and, as viewed in Figure 2, certain portions of the ribs 4 project into the longitudinal spaces between the ribs 5, or, in other words, overlap the area between the latter ribs. Thus, although the various ribs 4 and 5 are separated from each other, no transverse line extending from one edge of the plate to the other, at any point between the reinforcing ribs 4 and 5 at the upper and lower ends of said plate, can be traced which will not cut at least two separated points of the stiffening ribs. By this construction, not only will the appearance of the plate be improved, but the same may be made of relatively thin material, thereby reducing the manufacturing cost, and the plate will not warp.

The upper edge 6 of the plate 1 is bent upwardly, while the lower edge 7 is bent in a reverse direction and provided with a flange 8 parallel to the plate, which will assist in supporting said plate on the next adjacent lower plate, as shown in Figure 4. By this arrangement, there is not only effected an improved reinforcing of the plate in a transverse direction, but also a twofold closing of the joint between two plates will be effected at the place where the upper plate overlaps the lower one, and, consequently, no moisture will be allowed to pass beneath the upper plate into the space between the same and the lower plate.

On the back of each plate angle pieces or hooks 9 are secured near the lower edge of the plate, and these hooks engage over the adjacent upper edge of the next lower plate. Projections 10 are formed in the plate adjacent the upper edge thereof and engage in corresponding depressions or grooves 11 in the hooks 9, whereby the plates are firmly connected together and held in proper position relative to each other.

For securing the plate 1 to a roof lath 12, 100

there is affixed on the back of said plate a clip 13 providing a space between the same and the under surface of the plate into which a portion of a separate angle piece 14 may be inserted. The lower branch or portion of this piece 14 forms a hook which engages the lath 12. In order to secure the angle piece 14 in proper position within the clip 13, the upper portion of the piece 14 is provided with a projection 15 which engages in a corresponding opening 16 in the clip 13.

Instead of employing the clip 13, there may be secured to the under side of the plate 1, as shown in Figure 6, an angle piece 17 provided with a toothed lower edge 18 which is to be forced directly into the lath 12 for firmly securing the plate thereto.

What is claimed is:

A roofing construction including super-
posed sheet metal plates in which the lower
edge of the upper plate is bent and provided
with a flange parallel to said plate and en-
gaging the upper portion of the lower plate,
and wherein the latter plate has its upper
edge bent upwardly to engage the under sur-
face of the upper plate, and a hook member
receiving the upper bent edge of the lower
plate, and said hook member and lower plate
being formed with cooperating projections
and depressions for interlocking said plates.

In testimony whereof, I have affixed my
signature.

REGINA LÖWY,
35 *Administratrix of the Estate of Sigmund
Bauer, Deceased.*
